UNITED STATES PATENT OFFICE

OTTO CHRISTENSEN KROGH, OF ODENSE, DENMARK

VACUUM PROPELLER PLANE

Application filed June 27, 1931, Serial No. 547,380, and in Denmark July 29, 1930.

My invention relates to a vacuum propeller plane, consisting of a plain, circular disk on one side of which are mounted air-rarefying planes, which, when rotating together with the said disk, will produce a lower pressure than the atmospherical pressure on the side of the disk to which they are fixed, while the opposite side of the disk approximately is subjected to the pressure of the atmosphere.

The produced difference of pressure can be utilized for propulsion of a body in the direction of the axis of the rotation shaft, for instance for aeroplanes, or for producing air currents for ventilation purposes, dust suckers and the like.

It is well-known that the bearing-planes of aeroplanes are current-line shaped in order to produce, by a certain speed, a lower pressure (vacuum) on the upper side of the planes, which in co-action with the pressure on the under side gives the necessary buoyancy to the aeroplanes.

It is also well-known to give the air-propeller blades a current-line shaped fore-side, by which means a lower pressure is produced on this fore-side, whilst the back side, which is placed aslant presses the air together, if anything, but as the air can stream freely from the front to the back side in the rotation plane of the propeller, the produced vacuum is not turned to account to such a degree as by my invention.

By means of my vacuum propeller plane it is possible to obtain a considerably greater buoyancy or propulsion than by formerly used elements.

When utilized in aeroplanes their safety will increase, and they will be able to go vertically upward, to stand still in the air, or to land without the often so fatal sliding flight.

In the ventilation technics the invention can be utilized in agricultural machines, drying installations, dust suckers and the like.

My invention is illustrated in the accompanying drawing, in which

Figure 1 shows the vacuum propeller plane in top view;

Fig. 2 a section on the line A—B, in Fig. 1;

Fig. 3 a section on the line C—D, in Fig. 1, and

Fig. 4 the vacuum propeller plane in perspective, whilst Fig. 5 shows a number of vacuum planes decreasing in radiate direction and mounted on a common shaft.

In Fig. 1 a round disk 1 is provided with a shaft 2, the hub of which is concentrical with the disk.

Two air-rarefying planes 3 and 4 are mounted on the disk 1 in such a manner that they turn their current-line shaped side upward, while their plain under side is fastened to the disk 1.

The fore-edges 5 and 6 of the air-rarefying planes 3 and 4 are lying radiately on the disk 1, and the back edges 7 and 8, which are parallel with the fore-edges 5 and 6, form tangents to the circumference of the disk 1.

Figs. 2 and 3 show sections of the air-rarefying planes, in the left and the right side relatively. The air-rarefying planes are hollow and made in a manner like that of the bearing-planes of an aeroplane.

In Fig. 4 the arrow indicates the direction of the rotation of the vacuum propeller plane.

By the quick rotation of the vacuum propeller plane the relative movement of the air, immediately above the air-rarefying planes, partly will follow current-lines, by which means the lower pressure as known from the current-line theory is produced on the upper side of the air-rarefying planes. The underside of the disk 1 being plain, nearly a normal air-pressure will be reigning here.

As the air-rarefying planes 3 and 4 are connected mutually by the disk 1, the pieces 9 and 10 of the disk, see Fig. 4, will prevent a balancing of the pressure so that the vacuum produced by the planes 3 and 4 gets active on the whole area of the disk 1, and thus the superiority of my vacuum propeller plane, as to utilizing the obtained difference of pressure, is fully explained. Instead of straight back sides 7 and 8, the back side of the air-rarefying planes can be shaped according to the periphery of the disk, and the cross-section of the air-rarefying planes can decrease in the direction of the radius of the

disk 1, in order to make the formation of the current-line as easy as possible.

Having thus described my invention, I claim:

- 5 1. In vacuum propeller planes the combination, with a circular disk, of a number of current-line shaped air-rarefying planes mounted on one side of the said disk, and means for rotating the said disk in order to
- 10 obtain a lower pressure all over its area on that side, on which the air-rarefying planes are mounted.
- 15 2. In vacuum propeller planes the combination, with a disk, of air-rarefying planes mutually connected by the said disk and having their back sides shaped according to the periphery of the disk, on one side of which they are mounted.
- 20 3. In vacuum propeller planes the combination, with a disk, of air-rarefying planes mounted on one side of the disk, and the cross section of which decreases outward in radiate direction, corresponding to the speed.
- 25 4. In vacuum propeller planes the combination of at least one disk on one side of which air-rarefying planes are mounted, a number of groups of such planes, and a common shaft.

In witness whereof I have hereunto set
30 my hand.

OTTO CHRISTENSEN KROGH.
